BALANCING AND WALKING DEVICE

Therese C. Abdallah, Seattle, Wash.

Application February 4, 1952, Serial No. 269,784

10 Claims. (Cl. 155—23)

1

This invention relates to a balancing and walking device and particularly a therapeutic device for supporting spastic children while they learn to walk.

In teaching spastic children to walk it is often found that they are very rigid and are a dead weight to lift and so extremely hard to work with. Not only is it necessary to support the spastic child in an upright position which requires extreme strength, but is also frequently necessary to have to utilize the operator's hands to move the feet and legs of the patient. It is therefore frequently extremely difficult for the physical therapist to support the patient while at the same time moving the legs in a more or less natural walking fashion. A variety of hoist type devices have heretofore been constructed for assisting a physical therapist in supporting a patient while teaching him to walk.

The present invention provides an overhead carriage having a pendulant supporting arm engaging the body of the patient so that the patient may move in a substantially straight line and will not have lateral motion so that the patient may be supported in a safe and careful manner while the therapist has his hands free to operate the limbs and feet of the patient.

It is accordingly an object of this invention to provide an improved physical therapy lift.

It is a further object of this invention to provide a walking and balancing device for a spastic patient.

It is a further object of this invention to provide a supporting mechanism in which a patient may move in a substantially straight line, but is supported in a lateral direction.

It is a further object of this invention to provide a supporting mechanism which can be anchored to the pedal extremities of the patient so that the body supporting mechanism will not be uncomfortably raised.

Other objects and many of the attendant advantages of this invention will be apparent from the following detailed description taken in conjunction with the accompanying drawings in which:

Figure 1 is an elevation with parts in section showing a balancing and walking device according to this invention;

Figure 2 is an end view of the supporting device as shown in Figure 1;

Figure 3 is a top plan view of the walking and balancing device showing the manner of connection;

Figure 4 is an enlarged detail view of the swivel

2

joint of the cross member taken substantially on the plane indicated by the line 4—4 of Figure 3;

Figure 5 is a cross-sectional view in enlarged detail of the horizontal swivel taken substantially on the plane indicated by the line 5—5 of Figure 3;

Figure 6 is an enlarged detail cross-section of the mounting of the carriage on the overhead track taken substantially on the plane indicated by the line 6—6 of Figure 3;

Figure 7 is an enlarged detail sectional view through the vertical swivel joint taken substantially on the plane indicated by the line 7—7 of Figure 2; and

Figure 8 is a perspective view of the body supporting jacket according to the invention.

In the exemplary embodiment of the invention an overhead track 10 and 12 is supported on suitable legs 14 herein shown as four in number although obviously any length track can be used supported on any number of legs. An overhead carriage comprises a pair of rail engaging members 16 and 18 having rollers 20 for engagement with the tracks 10 and 12. The rail engaging members 16 and 18 are connected by rigid cross members herein indicated as a pair of rod- or pipe-like members rigidly secured to the rail engaging members 16 and 18 by any suitable means such as welding. The central portion of the cross member is swiveled with respect to the end members so that the central portion is free to move in an oscillatory fashion in a plane parallel to the rail members or in other words in a plane transverse to the cross members. Preferably the swivel joint is provided with ball or roller bearing members so that the oscillation will be quite free.

Centrally supported in the cross bars 22 and 24 is a clamp plate having front members 30 and back members 32 through which extends a vertically adjustable U-shaped bar 34 which may be adjusted to any desired position between the plates 30 and 32 and held in position by means of a clamping screw 36 having a wing nut 38. A bottom terminal for the pendulant U-shaped member 34 comprises a swivel having a plate 40 attached to the bottom ends of the U-shaped member 34. The plate 40 is provided with a cup-shaped depression having an opening 44 through which is journaled an end piece 46 having secured thereon a bearing plate 48 and locked in position by means of a nut 50. The end piece 46 has rigidly attached thereto a semi-rigid inverted U-shaped support member 52 which provides a bifurcated lower end to the pendulant member which may be placed around or adjacent

to the head of the patient so that the head of the patient is laterally supported. Preferably the member 52 is provided with suitable padding 54 so that the head of the patient may not be injured by accidental contact with the bifurcated member 52.

A body engaging member is provided in the form of a leather jacket 60 having a plurality of adjustable members such as buckle straps 62 in the front and a plurality of similar adjustable straps 64 in the back so that the leather jacket can be adjusted snugly to the body of the patient. Shoulder straps 66 and 68 are also provided on the jacket and are likewise adjustable to the size of the patient by means of suitable adjustable means such as the buckles 70. The shoulder straps 66 and 68 carry upstanding ear or U-shaped members 72 and 74 for engagement with the bifurcated end of the pendulant support. The lower ends of the inverted U-shaped member 52 are provided with snaps 76 and 78 for engagement with the upstanding ears 72 and 74. In this manner a jacket 60 can be adjusted to the body of the patient and the inner structure may be adjusted with respect to the horizontal carriage by means of the pendulant member 34 and the shoulder straps 66 and 68.

In order to prevent the jacket 60 from riding up under the arms or under the chin of the patient suitable legging-like members 80 are applied to the lower limbs of the patient and have straps 82 extending under the pedal extremities or feet so that the legging-like members 80 are securely attached to the lower extremities of the patient. A plurality of straps 86 and 88 are attached to the backs and front respectively of the legging-like members and are secured to suitable adjusting means such as buckles 90 and 92 on the bottom of the jacket 60.

In operating the device the pendulant member will be adjusted so that the snaps 76 and 78 will properly engage the shoulder supports or ears 72 and 74 of the jacket 60 which is firmly secured around the body of the patient and also firmly secured to the pedal extremities of the patient so that the jacket is properly anchored on the mid-portion of the patient. The pendulant member is substantially bifurcated by means of an inverted U-shaped member swivelly attached at a portion intermediate the pendulant member. The pendulant member is free to swing in a front or backward position substantially in a plane parallel to the planes of the tracks by means of swivel members 26 and 28 but it is substantially rigid to any lateral motion so that the patient is unable to fall sidewise. Hand rails 96 and 98 are preferably provided alongside the patient so that he may use his hands to assist himself in moving along the track. Preferably the rails 96 and 98 are received in brackets 100 and 102 mounted on the post 14 and the brackets 100 and 102 are provided with a plurality of openings 104 so that the rails 96 and 98 may be inserted at any desired height to accommodate the patient. The patient while supported in this walking and balancing device may move along with the assistance of his own hands on the rails 96 and 98 while the physical therapist may manipulate the pedal extremities of the patient. The swivel member is the pendulant element that permits the patient to turn completely around so that after he has finished the length of the bar in one direction he may turn around and go in the other direction, however, he will be at all times protected against lateral movement be-

cause of the substantially rigid mounting of the pendulant member with respect to any lateral motion.

While for purpose of illustration a specific embodiment of the invention has been disclosed and the same has been described according to the best of my present understanding thereof, it will be understood, that many changes and modifications can be made therein, without departing from the spirit of my invention.

Having described the invention, what is claimed as new is:

1. A walking device for training patients to walk comprising a track including a pair of spaced apart rails, track engaging means on each rail, a frame extending between said track engaging means, swivel means in said frame whereby a portion of said frame may oscillate with respect to said track engaging means, a clamp mounted on said portion, a support including a pair of parallel rodlike members, said support being adjustably secured in said clamp, a terminal rotatably mounted on said support, and means for releasably attaching said terminal to a body engaging member.

2. A walking device for training patients to walk comprising a track including a pair of spaced apart rails, track engaging means on each rail, a frame extending between said track engaging means, swivel means in said frame whereby a portion of said frame may oscillate with respect to said track engaging means, a clamp mounted on said portion, a support including a pair of parallel rodlike members, said support adjustably secured in said clamp, a terminal rotatably mounted on said support, and a substantially rigid inverted U-shaped connecting member mounted on said terminal.

3. A walking device for training patients to walk comprising an overhead track, a carriage mounted on said track, a pendulant support adjustably secured on said carriage, said support being journaled on said carriage for swinging movement in a plane parallel to the track while being substantially rigid in a direction transverse to said track, and means for suspending a body embracing member from said support.

4. A walking device for training patients to walk comprising an overhead track, a carriage mounted on said track, a pendulant support adjustably secured on said carriage, said support being journaled on said carriage for swinging movement in a plane parallel to the track while being substantially rigid in a direction transverse to said track, and means on said support substantially limiting lateral movement of the head of a patient.

5. A walking machine comprising an overhead track, a carriage mounted for movement along said track, a pendulant support secured on said carriage, a bifurcated terminal on said support, means for embracing the body of a patient, shoulder straps on said means, fastener means for connecting said bifurcated terminal to said shoulder straps, and swivel means interposed between said support and said bifurcated terminal.

6. For use in a walking machine having an overhead track, a pendulant support mounted on the track and having a bifurcated terminal, a jacket for embracing the body of a patient, shoulder straps on said jacket, means for connecting said bifurcated terminal to said shoulder straps, swivel means interposed between said support and said bifurcated terminal, means for securing said jacket to the lower extremities of

a patient, a side bar for cooperation with said support and means for adjusting the position of said side bar.

7. A therapy device comprising a substantially rod like track, a carriage including a substantially tubular member engaging said track, a plurality of roller means between said member and said track, a support depending from said carriage, said support including a pair of substantially parallel rodlike members, a plate rigidly secured to the end of said members, a bracket swiveled in said plate, a substantially rigid inverted U-shaped member secured on said bracket, and snaps secured adjacent the lower ends of said U-shaped member for detachably connecting said U-shaped member to a body engaging member.

8. A therapy device comprising a substantially rodlike track, a carriage including a substantially tubular member engaging said track, a plurality of roller means between said member and said track, a support depending from said carriage, said support including a pair of substantially parallel rodlike members, a plate rigidly secured to the end of said members, a bracket swiveled in said plate, a substantially rigid inverted U-shaped member secured on said bracket, a body engaging jacket, a pair of shoulder straps adjustably secured to said jacket, upstanding apertured means on each of said shoulder straps, snaps secured adjacent the lower ends of said U-shaped member for detachably connecting said jacket to said U-shaped member, leg engaging means for attachment to the lower extremities of a patient and straps attaching said means to said jacket.

9. A therapy device comprising an elevated track including a pair of parallel spaced apart rodlike rails, a substantially tubular rail engaging member on each of said rails, a rigid cross member connecting said rail engaging members,

a central portion of said cross member being free to oscillate in a plane transverse to the cross member, a pendulant U-shaped bar secured to said central portion, said U-shaped bar being vertically adjustable, a swivel plate attached to the bottom of said pendulant U-shaped member, and an inverted U-shaped support member swivelly mounted on said swivel plate.

10. A therapy device comprising an elevated track including a pair of parallel spaced apart rodlike rails, a substantially tubular rail engaging member on each of said rails, a rigid cross member connecting said rail engaging members, a central portion of said cross member being free to oscillate in a plane transverse to the cross member, a pendulant U-shaped bar secured to said central portion, said U-shaped bar being vertically adjustable, a swivel plate attached to the bottom of said pendulant U-shaped member, 15 and an inverted U-shaped support member swivelly mounted on said swivel plate, detachable connectors mounted adjacent the lower ends of said U-shaped support member, said connectors being adapted to secure a body engaging means 20 to said device.
